UNITED STATES PATENT OFFICE.

LEOPOLD AVISUS, OF NEW YORK, N. Y., ASSIGNOR TO BRAMBACH PIANO COMPANY, OF NEW YORK, N. Y., A CORPORATION OF NEW YORK.

GRAND-PIANO CASE.

1,160,969.

Specification of Letters Patent.

Patented Nov. 16, 1915.

Application filed November 1, 1912, Serial No. 728,973. Renewed October 6, 1915. Serial No. 54,433.

To all whom it may concern:

Be it known that I, LEOPOLD AVISUS, a citizen of the United States, residing at New York, in the county of New York and State 5 of New York, have invented a new and useful Grand-Piano Case, of which the following is a specification.

As heretofore constructed, so far as I am aware, grand piano cases have been provided with cheek pieces integral and continuous with the strip which extends around the rear of the case and forms the rear and side walls. Owing to the peculiar shape of this piece and the treatment which it has to 15 receive in giving it that shape, it has a tendency to warp ordinarily, and the effect of this warping is particularly noticeable on the ends or cheeks thereof. It is also necessary to use long pieces of wood of the same 20 thickness as the cheeks, and this, as is well understood, adds materially to the expense, as pieces which have no imperfections throughout are more expensive than small pieces of the same grade.

25 The principal objects of this invention are to eliminate these difficulties, and to provide a construction in which the warping of the long strip will be less apparent in the cheek pieces, and in fact will have very little 30 effect upon them; a construction in which the cheek pieces themselves tend to strengthen and hold the ends of the back strip and prevent their displacement, and in which relatively small pieces can be employed; also to provide a construction in 35 which a vertical line will appear at the rear of each cheek piece, thus giving the casing the appearance of being made of thicker material and adding to the beauty thereof.

40 Reference is to be had to the accompanying drawings, in which—

Figure 1 is a side elevation of the front part of a grand piano case with a preferred form of this invention applied thereto; Fig. 45 2 is a similar view of the cheek and a part of the back strip separated from each other; Fig. 3 is a sectional view on the line 3—3 of Fig. 1 on enlarged scale; and Fig. 4 is a plan of the cheek and back strip on reduced scale. 50 The invention is shown as applied to a grand piano casing of a well known type. In this case the back strip A, which extends around the back and along the sides or ends for a distance, is made preferably of a single

piece of wood and extends only to the edges 55 which ordinarily constitute the cheeks thereof, that is, to a place at the side of the instrument, not far from the front. At this point this strip is provided with a pair of vertical terminal tenons a. Fitting on the 60 ends of this strip are a pair of cheek pieces B, each having a notch on the outer side and, at the end of the notch a mortise into which 65 said tenons fit. Each also is provided with a tongue b extending beyond the end of the back piece inside so as to provide at the end thereof a vertical line formed by the end 70 surface of the tongue overlapping the flat surface of the piece A. It will be noticed that the cheek piece B is more than twice as 75 thick as the member A, and that the latter engages the cheek piece at one side of the center thereof so as to provide a projecting outside vertical corner b' and permit the use of a cheek-piece materially heavier than the 80 back strip. This permits the use of a relatively thin back strip which in itself reduces the expense of course, but which has the additional advantage of permitting the bending and manipulation thereof at a reduced 85 expense and also with more accuracy.

It will be seen that by uniting the parts as shown in Fig. 3, and gluing the abutting surfaces the back strip is materially strengthened and supported all along its 85 front edge by the heavy cheek piece. In this way the tendency to warp is effectively resisted and the parts kept firmly in position.

Although I have illustrated and described 90 only one embodiment of the invention, I am aware of the fact that many changes can be made therein by any person skilled in the art without departing from the scope of the invention as expressed in the claims. Therefore, I do not wish to be limited to all the 95 details of construction herein shown and described, but

What I do claim is:—

1. As an article of manufacture, a grand 100 piano case having a rear strip extending around to the sides or ends of the instrument and terminating at a distance from the front thereof, and a cheek formed of material substantially twice as thick as said rear 105 part, mortised vertically to the end thereof at the outer side to support and hold the end of the rear strip in position and having a

tongue extending rearwardly along the inner surface of the rear strip to strengthen the joint.

2. As an article of manufacture, a grand piano case having a rear part extending around to the sides or ends near the front and provided with terminal vertical central tenons, and a pair of cheek pieces formed of material thicker than the rear piece and each 10 having a vertical notch on the outer side thereof and a mortise at the end of said notch beyond the center of the cheek piece for receiving said tenon.

3. As an article of manufacture, a grand piano case having a rear part extending around to the sides or ends near the front and provided with terminal vertical tenons, and a pair of cheek pieces formed of mate-

rial thicker than the rear piece and each having a vertical notch on the outer side 20 thereof terminating in a vertical outside corner and a mortise at the end of said notch for receiving said tenon, the ends of the rear piece fitting into said notch and against the surface thereof inside said corner, whereby 25 the cheeks strengthen and support the ends of the rear piece and provide a vertical projection along the edge thereof.

In testimony whereof I have hereunto set my hand, in the presence of two subscribing 30 witnesses.

LEOPOLD AVISUS.
